UNITED STATES PATENT OFFICE.

ALBERT F. STROUSE, OF PHILADELPHIA, PENNSYLVANIA, ASSIGNOR TO WESTINGHOUSE ELECTRIC & MANUFACTURING COMPANY, A CORPORATION OF PENNSYLVANIA.

MEANS FOR DELIVERING COAL TO HOPPERS OF CONTINUOUS FUEL-FEED STOKERS.

Application filed May 1, 1925. Serial No. 27,323.

My invention relates to an apparatus for retorts. In my device a retort which is directly under one chute will also be near the end of the spreader of an adjacent row, while those under the end of the spreader of the same chute will be under the chute of another row. The intermediate retorts will be under the intermediate portions of the spreaders of two rows. For this reason all retorts will receive a fuel of substantially similar characteristics.

Another object of my invention is to provide a stoker such that if one chute becomes clogged the retorts immediately below it will receive fuel from other chutes. A still further object is to produce a device of the described character which will be simple yet positive in operation, easily made, inexpensive in construction yet durable.

These and other objects of my invention will be evident from the following specification and claims having reference to the accompanying drawings in which Fig. 1 is a front view of the hopper of a multiple retort stoker with one embodiment of my device applied thereto; Fig. 2 is a plan view showing the chutes in section; Fig. 3 is a section on line III—III of Fig. 2.

In constructing a device embodying my invention I may use a progressive fuel feed stoker having a fuel hopper extending along the front of the furnace. A number of chutes are arranged in staggered relation in two rows. These chutes are provided with spreaders, the spreaders of one row overlapping with those of the other row.

In my preferred embodiment, which is shown in the accompanying drawing, the hopper 10 of a multiple retort stoker is located above the ram boxes 11 which are of a well-known type. The fuel is supplied to the hopper through chutes 13—14, these being arranged in two rows, the chutes 14 of one row being spaced intermediate the chutes 13 of the other row. At the bottom of each chute is a spreader 16. These spreaders are wider than the distance between the chute of one row and the corresponding chute of the other row which, causes them to overlap for a considerable part of their distance. In feeding the fuel through the chutes there is a tendency to segregation and if the chutes do not overlap the lumps are fed to the retort directly under the chutes and the fine coal is fed to the intermediate

Furthermore, should one of the chutes become clogged, the retorts receiving fuel from this chute will not run with a diminished fuel supply for the retorts will receive fuel from the spreaders of the other row although the character of the coal will not be of such uniform quantity as would be the case when the retort is receiving fuel from two spreaders. While this condition is not, of course, desirable, yet it causes far less serious difficulties than the complete failure of the fuel supply to a retort.

While I have shown my invention in but one form, it will be obvious to those skilled in the art that it is not so limited, but is susceptible of various changes and modifications, without departing from the spirit thereof, and I desire, therefore, that only such limitations shall be placed thereupon as are imposed by the prior art or as are specifically set forth in the appended claims.

What I claim is:—

1. In combination with a multiple retort stoker, a hopper for said stoker, a plurality of chutes having discharge ends arranged to discharge into said hopper, said discharge ends being arranged in a plurality of rows and the discharge ends of one row being staggered with respect to the discharge ends of the other row.

2. In combination with a multiple retort stoker, a hopper for said stoker, a plurality of rows of chutes for said hopper, the chutes of one row being offset with respect to the chutes of the other rows and spreaders between said chutes and said hopper.

3. In combination with a multiple retort stoker, a hopper for said stoker, a plurality of rows of chutes for said hopper, the chutes of one row being offset with respect to the chutes of the other rows and spreaders between said chutes and said hopper, the spreaders of one row overlapping those of the other rows.

4. In combination with a progressive fuel feed furnace, a hopper, means for supplying fuel from said hopper to said furnace, a plurality of fuel conduits arranged parallel to each other and discharging into said hopper, said conduits being so arranged that the zones of fuel supply of said conduits overlap.
5. In combination with a hopper of a progressive fuel feed furnace, a plurality of fuel conduits discharging into said hopper, said conduits being arranged in at least two rows and provided with spreaders, the spreaders of the conduits overlapping.
6. In combination with a progressive fuel feed furnace, a hopper, means for supplying fuel from said hopper to said furnace, and a

plurality of series of fuel conduits arranged in parallel relation to each other and discharging into said hopper, said series of conduits being so arranged that the zones of fuel supply of said conduits overlap.

20

7. In combination with a progressive fuel feed furnace, a hopper, means for supplying fuel from said hopper to said furnace, and a plurality of series of vertically disposed fuel conduits arranged in parallel relation to each other and discharging into said hopper, said conduits being so arranged that the zones of fuel supply of said conduits overlap.

25

In testimony whereof, I have hereunto subscribed my name this eighth day of April, 1925.

ALBERT F. STROUSE.
